VALENTINE FATH, PHILIP FATH, AND JULIUS FRIELINGSDORF,
OF ST. LOUIS, MISSOURI.

Letters Patent No. 85,003, dated December 15, 1868.

IMPROVEMENT IN SOLDERING-MACHINES.

The Schedule referred to in these Letters Patent and making part of the same.

To all whom it may concern:

Be it known that we, VALENTINE FATH, PHILIP FATH, and JULIUS FRIELINGSDORF, of St. Louis, in the county of St. Louis, and State of Missouri, have made certain new and useful Improvements in Machine for Soldering Water-Gutter; and we do hereby declare that the following is a full and clear description thereof, reference being had to the accompanying drawings, and to the letters of reference marked thereon.

The object of this invention is to construct a machine for holding the several pieces or sheets of tin, or other metal of which a water-gutter or eaves-trough is composed, in the proper position for soldering, and in a straight line.

We are well aware that other machines are now in use for the same purpose, but that, being imperfectly adapted to the business, they are almost entirely worthless.

These other machines, to which we allude, have usually convex bed-pieces, to which the concave sides of the metal sheets are secured by means of spring-hasps.

In this manner the gutter is formed bottom side up, and in this position the completed gutter is so yielding and flexible, that it is impossible to construct anything but very short sections of gutter at one operation, owing to the deflection of the overhanging ends thereof.

Guttering constructed in this manner is open to the still further objection that its joints are soldered only on the outside, and for this reason it is often found impossible to discover and repair leaky joints without removing the gutter from the building.

It is to remedy the defects of this kind in existing machines, that the present machine is provided.

Briefly, it consists of a hollow trough, in which the various sections or sheets of metal intended to form a gutter are placed, and held, by means of spring-clamps, in such positions as to be soldered to one another, as required. The said trough, by being hung on trunnions, may be turned to either side, so as to always solder on the bottom place of the seam.

To enable those skilled in the art to make and use our improved soldering-machine, we will proceed to describe its construction and operation.

Figure 1, of the drawings, is an end elevation of the improved machine.

Figure 2 is a plan of the same.

The concave trough A has trunnions *a* on its ends, which rest on the posts or standards B, that are erected on the platform B'.

This trough should be long enough to hold three or four (more or less) sheets or pieces C C' C'', in the proper positions for forming a water-gutter.

Spring-clamps, D D' D'' D''', are secured to the sides of the trough, and arranged to fold down into the trough in pairs, and their ends turning over at *d*, in scrolls, will so spring together, as is shown in fig. 2, as to hold the said sheets down tightly to the trough until their joints *c* are soldered.

The first two pairs of these clamps, D D', should be placed the proper distance apart to allow both of the said pairs of clamps to fall on the same piece or sheet C, while the remaining distances between D', and D'', and D''' are just sufficient to allow one of the said clamps to fall on one of the additional pieces C' C''.

When a section of the gutter formed in this manner has been fully soldered, the clamps may be loosened, and the completed piece shoved along toward the end of the trough, when new sheets will be inserted in the trough, clamped, and soldered as before.

In this way a long gutter may be formed, without the danger of the overhanging end sagging so as to misshape the piece.

The curled edge *c'* may be placed on either side, so as to make the gutter dip in either direction, without running the water against the joints—a valuable feature of the invention, which cannot be attained in any machine now in use, owing to the inequality of the distances between the clamps D D' D'' D''', as above described.

By hanging the trough A on trunnions *a*, it may be turned to either side by the operator, so as to solder at the bottom of the groove at all times—a position for soldering, of manifest advantage, owing to the fluid condition of the solder.

The pins *a'*, projecting from the ends of the trough, will strike the posts B, so as to prevent the trough from tipping over too far.

By using the trough A as above described, the cross-stays may be inserted in and secured to the gutter, at the time of manufacturing the same.

Having described our invention,

What we claim, is—

The trough A, supported by trunnions *a* and the stops *a'*, and in combination with the clamps D D' D'' D''', substantially as and for the purpose set forth.

In testimony of which invention, we hereunto set our hands, in presence of—

VALENTINE FATH.

PHILIP FATH.

JULIUS FRIELINGSDORF.
